UNITED STATES PATENT OFFICE.

CHARLES PIERCE AND LEROY H. SMITH, OF ITHACA, NEW YORK, ASSIGNORS
TO THE ITHACA GUN COMPANY, OF SAME PLACE.

LOCK MECHANISM FOR BREECH-LOADING GUNS.

SPECIFICATION forming part of Letters Patent No. 369,812, dated September 13, 1887.

Application filed May 11, 1887. Serial No. 237,799. (No model.)

To all whom it may concern:

Be it known that we, CHARLES PIERCE and LEROY H. SMITH, citizens of the United States, residing at Ithaca, in the county of Tompkins and State of New York, have invented certain new and useful Improvements in Lock Mechanisms for Breech-Loading Guns, of which the following is a full, clear, and exact description, which will enable any one skilled in the art to which it appertains to construct and use the same, reference being had to the accompanying drawings, which form a part of this specification.

This invention relates to the lock mechanism of breech-loading guns of the class having concealed hammers, and known as "hammerless;" and it consists, first, in improved mechanism by which the hammers are cocked; second, in improved devices by which the hammers are held safely in the cocked position and released at will, so that the gun may be fired; third, in an improved mode of constructing what are known as the "top-lever" and "locking-bolt," whereby said parts are simplified and rendered very compact; fourth, in an improved method of arranging the mainspring and hammer, so that the latter is caused to rebound after firing.

Our invention is fully illustrated in the accompanying drawings, in which Figure I is a plan view of our improved gun-lock, the barrels being removed the better to show the working parts. Figs. II and III are side elevations, partly in section, the section being taken on the broken line *a*, Fig. I, showing the devices employed for cocking the gun, rendering the lock "safe," and firing. Fig. II represents the gun "broken" and at full-cock, and Fig. III shows the various parts of the lock in position after firing. Fig. IV is a central sectional side elevation exhibiting our improved locking-bolt and its connections. Figs. V and VI are enlarged detail views of our improved hammers in side and rear elevation, respectively. Fig. VII is an enlarged plan, partly in section, of the locking-bolt and shank operating the same, the latter being inverted. Fig. VIII is an enlarged perspective view of the safety-clutch.

The letter A designates the stationary breech-block, which is suitably recessed in the

usual manner to form a case for the various operative parts of the lock. The upper rear portion of said breech-block is formed into a tang, A', and to the lower side of said block is fitted a trigger-plate, A'', said tang and trigger-plate being adapted for the attachment of a wooden stock.

The hammers B are inclosed within the breech-block A, and are pivoted upon pins C, 6c secured in said breech-block. Said hammers are arranged to oscillate lengthwise of the breech-block, with the striking parts uppermost and in line with the firing-pins D. The hammers are actuated by looped mainsprings E, arranged in suitable recesses in the front part of the breech-block. The particular arrangement of these parts will be further described.

We will now explain the mechanism for cocking the gun. Each of the hammers is laterally recessed for a short distance from its lower edge upon the side toward the middle of the lock. Said recess is so formed that the lower edge of the thicker portion of the hammer above it is an oblique curve, to be termed the "hammer-cam." This construction is fully shown in Figs. V and VI.

H H are two similar parallel levers extending lengthwise of the lock, which we call the "side levers." Said side levers are inclosed within the breech-block, and are pivoted at their rear ends upon a stationary pin, I, fixed transversely in the lower rear portion of said block, and connected together at their forward ends by a transverse pin, J.

The gun-barrels K are pivoted in the usual manner to the front portion of the breech-block, and are provided with a cocking-hook, L, rigidly fixed centrally upon the lower side 90 of said barrels near the breech. Said cocking-hook engages with the side levers, H, through the medium of the pin J, so that the side levers are elevated by the upward tilting motion of the breech in "breaking" the gun. 95 The upper edges of the side levers engage at a point near the pin I with the forward portion of the hammer-cams G, so that the hammers are oscillated to the full-cock position by the upward movement of the side levers, H. It 100 will readily be seen that the operation of tilting the barrels in breaking the gun results in

cocking the hammers through the medium of the cocking-hook, side levers, and hammer-cams above described.

5 M M are the sears, centrally pivoted, preferably, upon the stationary pin I, and caused by the sear-springs N to engage with notches in the lower edges of the hammers B to hold said hammers at full-cock. Said sears are at their rear ends bent at a right angle across the 10 tops of the triggers P, which are centrally pivoted in slots in the trigger-plate A². The upper portions of said triggers extend forward of their pivots, and are provided with downwardly-projecting lugs near their forward 15 ends.

R is the safety-clutch, which consists of a flat bar of metal centrally placed below the tang A', to which it is secured by a screw passing through a slot in the bar R, allowing 20 said bar to be moved lengthwise for a short distance. This motion is effected by means of a thumb-plate, R², upon the upper side of the tang A', rigidly connected to the bar R by a stud passing through a longitudinal slot in 25 said tang. The bar R is prevented from moving accidentally by means of a spring, R³, secured to the lower side of tang A'. Said spring presses upwardly upon the bar R, and is arranged to engage with any one of three transverse notches, R⁴, upon the lower side of said bar, so that a considerable force is required to 30 move the bar.

The forward portion of the bar R is bent vertically downward, and is provided at the 35 lower end of said vertical portion with two opposite transversely-projecting arms, R⁵, to be termed the "safe-bolts." Said safe-bolts extend across the tops of the sears M, and are so arranged with reference to the triggers P that 40 when the safety-clutch bar R is moved to the position where the spring R³ is engaged with the middle notch, R⁴, the safe-bolts R⁵ are interposed between the downwardly-projecting lugs of the triggers and the sears. It is plain 45 that in this position the gun cannot be fired, as any pressure upon the triggers results in downward pressure of the safe-bolts upon the rear parts of the sears, forcing them into closer engagement with the notches of the hammers. 50 The parts of the triggers engaging with the safety-bolts may be slightly concave to embrace the safety-bolts and prevent them from being slipped out of place by pulling the triggers.

55 When the safety-clutch is moved forward or backward from the above-described position by means of the thumb-plate R², the safe-bolts R⁵ are disengaged from the triggers, and the gun may then be fired by upward pressure of 60 the rear portions of the triggers upon the rear bent parts of the sears.

When the gun is "broken," the safety-clutch bar R is pushed into its middle or "safe" position, above described, by means 65 of the locking-bolt T, mounted longitudinally in the breech-block. Said locking-bolt normally engages with a locking-hook, U, at-

tached to the barrels in the usual manner, and is moved lengthwise backward to release the barrels. The locking-bolt is by said movement forced against the safety-clutch bar R, 70 pressing said clutch into the safe position.

When it is not desired to use the safety-clutch, the bar R is retracted to its rear or "independent" position, where it is out of reach 75 of the locking-bolt, and the safe-bolts R⁵ are at the rear side of the downwardly-projecting lugs on the triggers, the safety-clutch being thus rendered inoperative.

Various devices have been employed to render breech-loading self-cocking guns safe, but in many cases the gun is accidentally fired by the displacement of the safety devices upon the return of the barrels to their normal position. This defect is entirely overcome by our 80 improved construction above described, which consists in automatically interposing a safe-bolt between the sear and a portion of the trigger, moving in a direction opposite to that required for disengaging the sear from the hammer, so that any external pressure upon the 85 trigger results in a pressure upon the sear in a direction opposite to that required to fire the gun.

The locking-bolt T is cylindrical, and is operated by the top lever, V, in the following manner: A vertical cylindrical shank, V', rigidly attached to said top lever, passes downwardly through a recess in the breech-block A. The lower end of shank V' terminates in a flat transverse blade, V², which engages with a transverse slot, T', in the upper side of the locking-bolt T. The rear side of said slot is perpendicular to the axis of said bolt, and the front side thereof is cut diagonally, so that the 90 narrowest part of said slot closely fits the blade V². By this construction the shank V' can be revolved in but one direction by the top lever, V, said revolution causing the retreat of the locking-bolt T. The return of said locking bolt 95 is effected by a strong open spiral spring, W, inclosed in a central longitudinal recess in the locking-bolt. Said spring encircles a cylindrical pin, X, of small diameter, and presses upon a head at the rear end of said pin of 100 larger diameter, forcing said head against the blade V², and causing said blade to assume its 105 normal position. The blade V², by its engagement with the slot T', prevents the locking-bolt T from revolving or advancing too 110 far.

The hammers are caused to rebound after firing by their peculiar arrangement with reference to the mainsprings E. The upper arms of said mainsprings press against the upper 115 walls of the recesses in which they are inclosed, as before described, and their lower arms press downwardly upon the front parts of the hammers. Said lower arms extend beyond the hammer-pivots C. When the hammers are at 120 rest after firing, their striking parts are not in contact with the firing-pins D; but said hammers are made to strike said pins in firing by the momentum imparted by the mainsprings, 125 130

and are slightly retracted by the downward pressure of the lower ends of said mainsprings upon the parts of the hammers beyond the pivots C.

5 We have arranged the spring upward and forward of the hammer, with its extreme end passing the pivot of the hammer, because that portion of the spring yields readily to pressure and offers little resistance to the hammer to blow, and the said end may be shortened or lengthened to adjust it to the exact amount of resistance required. Furthermore, by this arrangement the strong midway portion of the spring is brought to act upon the extreme 15 point of the hammer, insuring lively action of the hammer in service.

Having fully described our invention, we claim and desire to secure by Letters Patent—

1. In a breakdown breech-loading gun, the 20 combination of the hammer B, pivoted at C, and recessed at one side, forming the cam G, slanting forward of the pivot, and the lever H, pivoted at its rear end to the breech-block A and loosely connected at its forward end 25 with the barrel, the midway portion of the said lever bearing upward against the said cam G, forward of the pivot C, substantially as shown and described.

2. In a breech-loading self-cocking gun, the 30 combination, substantially as set forth, of the oscillating hammers B, laterally recessed at their lower parts to form oblique hammer-cams G, the side levers, H, pivoted at their rear ends to the breech-block A and connected together at their forward ends, said side levers being arranged to oscillate said hammers to full-cock position when elevated by engaging with said hammer-cams, and means actuated by the gun-barrels K for elevating said side levers by tilting said barrels 35 in breaking the gun.

40 3. In combination with a centrally-pivoted sear and a centrally-pivoted trigger arranged to elevate the rear part of said sear by up-

ward movement of the rear part of said trigger, a safety-bolt arranged to be interposed between the forward part of the trigger and the rear part of the sear to prevent said trigger from operating said sear, substantially as 45 described.

50 4. The combination of the locking-bolt T, fitted in the block A to slide longitudinally rearward to unlock the barrel, the safety-clutch bar R, fitted to slide longitudinally in the said block and provided with the T-shaped head or safety-bolts R⁵, and with an intermediate portion crossing the path of the bolt T, in the rear of the bolt, the sear M, pivoted at a point, I, forward of the bolts R⁵, and provided at the rear of the said bolts with a lateral extension, and a trigger, P, pivoted to the block A, at a point to the rear of the said bolts R⁵, and adapted to engage the lateral extension of the sear on its under side, the said trigger having an extension upward and forward of its pivot provided with a downwardly-projecting lug, the said lug and the sear being adapted to engage between them the safety-bolt R⁵, substantially as shown and described, whereby the action of the trigger is interrupted when 65 the bar R is pressed back by the retracted bolt T.

70 5. In a breech-loading gun, in combination with the top lever, V, shank V', operated by said top lever, flat blade V⁵, rigidly connected to said shank, and transversely-slotted locking-bolt T, said blade V⁵ engaging with said transverse slot, the pin X, and spring W, inclosed within said locking-bolt and arranged to return said locking-bolt to its normal position 75 by pressing against the flat blade V⁵, substantially as set forth.
